DRILL PRESS

Jacques K. Stanland, New York, N. Y.

Application May 2, 1947, Serial No. 138,778

Term of patent 3½ years

(Cl. D54—4)

To all whom it may concern:

Be it known that I, Jacques K. Stanland, a citizen of the United States of America, residing at New York, in the county of New York and State of New York, have invented a new, original, and ornamental Design for a Drill Press, of which the following is a specification, reference being had to the accompanying drawing, forming a part thereof.

In the drawing:

Fig. 1 is a perspective view of a drill press, showing the new design; and

Fig. 2 is a top plan view thereof.

I claim:

The ornamental design for a drill press, as shown.

JACQUES K. STANLAND.
